UNITED STATES PATENT OFFICE.

JAMES WILLIAM FULLER, OF ST. PAUL, MINNESOTA.

LAUNDRY BLUE.

SPECIFICATION forming part of Letters Patent No. 553,556, dated January 28, 1896.

Application filed May 21, 1894. Serial No. 511,990. (No specimens.)

To all whom it may concern:

Be it known that I, JAMES WILLIAM FULLER, a citizen of the United States, residing at St. Paul, county of Ramsey, and State of Minnesota, have invented a new and useful Improvement 5 in Methods of Reducing the Soluble Blue of Commerce into Tablet Form, of which the following is a specification.

This invention relates to laundry blue, and 10 has for its object to prevent waste of material, facilitate its handling, determine the measure of quantity for any given amount of work to be done, and increase its working capacity, thereby reducing the cost of this article to a mere nominal figure.

The following causes, among others, have heretofore operated against its economical use by the consumer: Sold in liquid form, the blue has to be bottled, corked, carefully 15 packed and shipped at a heavy expense, occupying, too, more space than is necessary for transportation and storage. In cold climates its use is almost impracticable, because of its liability to freeze, causing the breaking of 20 bottles and loss of their contents. Sold and shipped in powdered form, the boxes containing it have to be supplied with specially-prepared sifting-covers. The very handling and 25 use of it in this form lead to waste of substance. Sold and shipped in a solid bulky 30 form in the shape of balls or cakes a percentage of the blue is lost by friction, causing the substance to powder or break to pieces in course of transportation or careless 35 handling of same, and when the blue finally reaches the consumer it has to be handled and used in bags of cloth to hold the solid substance while dipped and agitated in the water to be blued, and these bags have to be thrown 40 away every time a new ball or cake is required. Another percentage is wasted in the way of absorption by and escape of the blue 45 from the bags when laid aside in a dripping wet condition. All this waste of material, labor and time, slight though it may be, considered in the aggregate, will amount to large proportions, in time, and cannot be ignored; but the 50 most objectionable feature of the handling and use of the blue in any of the forms heretofore used consists in the failure and uncertainty in fixing the exact measure of the quantity of blue necessary for any given

amount of washing to be done. This question is left entirely to conjecture. Hence waste is unavoidable. To supply this want of 55 certainty, and thus prevent waste of material, is one of the objects of my invention, which consists of condensing the soluble blue of commerce, as found, into tablet form of a practical convenient size. This object I accomplish by the following mode of procedure:

I use and thoroughly mix any given quantity of soluble blue as found (preferably that known in the market as "Prussian blue," having ferrocyanide of iron for its base) with 65 oxalic acid and yellow prussiate of potassium, each of said ingredients to be used in powdered form and equal parts in weight, and when so mixed I moisten the same with a weak solution of gum-arabic, gum-tragacanth, or 70 similar substances, in sufficient quantity to enable me to knead the substances into a tough plastic mass of material, which, while in a moist condition, I granulate by forcing the same through a sieve, thereby producing 75 granules of uniform size, which in a dry state are pressed by means of a tablet-machine or compressing device in common use for similar purposes into small tablets of circular form and about seven-sixteenths of an inch 80 in diameter by one-sixteenth of an inch in depth.

Experiments with and actual use of my tablets have established the fact that one tablet of the size specified supplies a sufficient 85 quantity of blue for one ordinary family washing, thus establishing a basis of measurement fixed and certain of the quantity of blue necessary for any given amount of washing to be done, small or large, thus solving the problem 90 of economical use. The simple dropping of a tablet into a cup of water settles the necessary quantity of blue required for an ordinary washing. For a larger one the number of tablets may be increased to suit the occasion, regard being had to the fact that a small, hard, smooth, light, flat tablet causes less 95 powdering by friction in transportation and at the same time is cleaner, more practical and convenient for the consumer to handle. I do not wish to be confined, however, to the exact form and proportion of my tablets. They may, if preferred, be enlarged to meet, 100 in a single tablet, the demands of a larger

washing, the chief object of my invention being to establish a popular form of use of laundry-blue in the shape of a tablet, or any other suitable form, embodying a sufficient quantity of blue to supply the demands of one ordinary family washing.

The tablets being dry are placed in small square boxes holding one hundred each ready for use.

10 The merits of my invention then, briefly stated, consist in so utilizing the coloring property of soluble blue, as found, by a process of concentration into the form specified, so that instead of lessening or impairing its 15 working capacity as such increases it to an extent never thought of before, thus effecting a saving to the consumer of more than one hundred per cent. in the outlay for an article of necessity in every household, a fact 20 easily demonstrated by comparison.

For precisely the same outlay—that is, for ten cents paid for blue in liquid form, sold in pint bottles, lasting for ordinary family washing a period not exceeding three months—

25 I make it possible for the consumer to do such ordinary family washing for a period of twenty-four months, or two years, by using

the blue in concentrated form, such as described. In other words, at the rate of one tablet sufficient for one washing I make a box 30 of tablets containing one hundred supply sufficient blue for a hundred washings.

I claim as my invention—

The process of compressing the soluble blue of commerce into the solid form of tablets, 35 consisting in the following method and means to carry the same into effect:—mixing Prussian blue with oxalic acid and yellow prussiate of potassium, all in powdered form and equal parts in weight; moistening the substances, thus mixed, with a weak solution of gum arabic; kneading it into a tough plastic mass of material; forcing the same through a sieve to form granules of uniform size, which in a thoroughly dry state are compressed into 40 tablets of the size described, and, for the purpose set forth.

In testimony whereof I have hereunto set my hand in presence of two subscribing witnesses.

JAMES WILLIAM FULLER.
